CULTIVATOR TOOTH

Filed Feb. 14, 1927

UNITED STATES PATENT OFFICE

HENRY J. NOLL, OF MILWAUKEE, WISCONSIN

CULTIVATOR TOOTH

Application filed February 14, 1927. Serial No. 168,013.

This invention relates to a cultivator tooth construction.

In cultivator teeth as heretofore constructed, it has been the usual practice to provide a bracket and a shank riveted thereto and to provide a detachable tooth. The universal practice has been to widen the shank materially at the point where it contacts with the tooth in an attempt to prevent twisting or turning of the tooth. The result of this construction is that the earth plowed up by the tooth banks against the enlarged or widened shank portion and consequently causes clogging. In addition to this, the earth is broken into relatively large chunks and is not suitably pulverized. Further, the widened shank contacting with the tooth would not adequately prevent turning as it was found impossible to hold the tooth in intimate contact with the shank to such an extent that the widened face of the shank would become effective.

This invention is designed to overcome the defects noted above and objects of such invention are to provide a tooth construction which utilizes a relatively narrow shank which may be no wider than the bracket and which is provided with means of a novel type to adequately prevent turning of the tooth and also to force the tooth into binding engagement with the base of the shank.

Further objects are to provide means for powdering up or breaking up the earth as it passes over the top of the tooth without, however, any danger of clogging as has heretofore been the case with the standard construction described above.

Further objects are to provide an eminently practical and simple construction which may be cheaply manufactured, which may be readily applied, and which automatically locks the tooth against turning and forces it into binding engagement with the bottom of the shank.

Embodiments of the invention are shown in the accompanying drawings in which:

Figure 1 is a face view of the construction with parts broken away;

Figure 2 is a side elevation with a part in section;

Figure 3 is a sectional view on the line 3—3 of Figure 1;

Figure 4 is a view corresponding to Figure 3 showing a modified form.

Referring to the drawings, particularly Figures 1, 2, and 3, it will be seen that the tooth is carried by usual bracket 1 which has permanently secured thereto the usual shank 2. The shank, however, is modified to the extent that it is of the same width throughout and does not widen at its lower end where it contacts with the upper face of the tooth 3 as has heretofore been the custom. This shank 2 may be riveted to the bracket, as indicated, or secured in any conventional way. The bracket widens at its lower portion and provides a bearing head 4 against which the back of the tooth contacts. This bracket is provided with a plurality of spaced nibs or projecting lugs 5, three of such lugs being shown in the form illustrated, although obviously, any number could be employed. The tooth is correspondingly recessed, as indicated at 6, and is held clamped tightly against the head 4, with the lugs or projections 5 socketed within the recess 6 so that the tooth is held in a secure manner against turning. Further, it is to be noted that the upper face of the tooth is slightly recessed to provide a bearing face 7 contacting with the bottom end of the relatively narrow shank 2.

The means for holding the tooth tightly against the bearing head of the bracket and also wedged upwardly against the bottom of the shank 2 comprise a bolt 8 (see Figure 3) whose head 9 is countersunk in the tooth and is also provided with a cylindrical portion 10 accurately fitting the cylindrical portion of the aperture in the tooth. This bolt is provided with a nut 11 which bears against the rear side of the head or bottom portion 4 of the bracket. It is to be noted from Figure 3, that the bracket 4 is provided with an aperture whose lower side slants as indicated at 12. A cam block or cam bushing 13 fits within the aperture and has a slanting face contacting with the slanting face 12 of the aperture. Obviously, from an inspection of Figure 3, it will be seen that when the nut is tightened that the slanting face of the bush-

ing rides on the slanting face 12 of the aperture and forces the tooth 3 upwardly, so that its top edge 7 contacts firmly with the bottom edge of the shank 2 and thus additionally locks the tooth against rotation.

5 The converse of the construction just shown may, of course, be used as illustrated in Figure 4. In this case, the portion 4' of the bracket corresponding to the portion 4 10 is provided with an aperture whose bottom edge slants rearwardly as indicated at 12'. A bushing 13' similarly contoured fits within the aperture and is forced inwardly by means of the nut 11 of the bolt 8. This causes the 15 tooth 3 to be forced upwardly into binding engagement with the bottom of the shank 2. In addition to this, each of these constructions causes the intimate locking of the projections 5 in the recess 6 of the tooth.

20 It is to be noted that the cylindrical portion 10 of the countersunk head of the bolt engaging within the cylindrical portion of the aperture through the tooth gives a firm bearing for the bolt against the tooth and 25 serves to transmit the upward thrust imparted to the bolt by the cam washer or bushing 13 or 13'.

30 In order to insure the adequate pulverizing of the earth or soil a pair of outwardly slanting or divergent tines 14 are carried by the head 4 of the bracket, as shown in Figures 1 and 2. These tines may consist of round rods whose lower ends are threaded into the bracket, as shown, the bracket being provided 35 with suitable offset portions to afford adequate bearing surface for the tooth and also to carry the tines. These tines provide a gradually increasing space between themselves and the shank 2, so that it is impossible 40 for earth to wedge between the tines and the shank. For example, if a clod of earth should temporarily become lodged between a tine and a shank of the tooth in the ordinary operation of the machine, it would be immediately 45 raised by the inwardly passing earth and, consequently, would move upwardly between the tine and the shank and be discharged in the larger portion of the space between such tine and shank. In this way, 50 it is utterly impossible to clog the tooth construction of this invention. In addition, it has been found that the tines thoroughly pulverize the earth in a more effective manner than has heretofore been possible.

55 It will be seen that a novel form of tooth construction has been provided in which the tooth is held against turning and is wedged tightly against the bottom of the shank to additionally secure it against turning. Further, it will be seen that the device is of simple construction and may be cheaply produced.

60 Although the invention has been described in considerable detail, such description is intended as illustrative rather than limiting

as the invention may be variously embodied and as the scope of such invention is to be determined as claimed.

I claim:

A tooth construction comprising a bracket, 70 a shank secured thereto and having a relatively narrow lower bearing face, said bracket having a bearing head, a tooth contacting with said bearing head, a bolt secured to said tooth and extending through 75 said bearing head, said bearing head having a cam-shaped aperture through which said bolt projects, a cam-shaped bushing carried by said bolt and cooperating with said aperture to force said tooth upwardly into binding engagement with the lower face of said shank, and cooperating means carried by said tooth and bearing head for resisting rotation of said tooth relatively to said bracket.

In testimony that I claim the foregoing I have hereunto set my hand at Milwaukee, in the county of Milwaukee and State of Wisconsin.

HENRY J. NOLL.
